ADJUSTING AND LOCKING MECHANISM FOR RECLINING CHAIRS

Filed May 29, 1950

UNITED STATES PATENT OFFICE

2,617,469

ADJUSTING AND LOCKING MECHANISM
FOR RECLINING CHAIRS

Alois Skok, Pasadena, Calif.

Application May 29, 1950, Serial No. 164,973

3 Claims. (Cl. 155—45)

1

This invention relates to improvements in locking devices and is directed particularly to an improved adjusting and locking mechanism designed particularly for reclining chairs.

A particular object of the present invention is to provide an adjusting and locking mechanism of the character stated which can be easily and quickly released and locked by actuation of a single control lever.

A further object is to provide a mechanism of the character stated comprising a pivotally mounted bolt for actuation relative to a fixed keeper bar, with a pivoted bolt actuator lever which not only functions to positively shift the bolt toward and away from said bar but also functions to lock the bolt against accidental movement when it is engaged with the bar and when it is disengaged therefrom.

Other objects and advantages of the invention will become apparent as the description of the same proceeds and the invention will be best understood from a consideration of the following detailed description taken in connection with the accompanying drawing forming a part of the specification, with the understanding, however, that the invention is not to be limited to the exact details of construction shown and described since obvious modifications will occur to a person skilled in the art.

In the drawing:

Figure 1 is a view in vertical front to rear section of a reclining chair showing the present invention in operative connection therewith, the chair back and seat being shifted to full reclining position.

Figure 2 is a detail view on an enlarged scale, of the locking mechanism in engaged position, its disengaged position being shown in broken lines.

Figure 3 is a sectional view taken substantially on the line 3—3 of Figure 2.

Figure 4 is a view in front elevation, on a reduced scale, of a chair structure constructed in accordance with the present invention, the upper part of the back being broken away.

Referring now more particularly to the drawing the numeral 10 designates one of the two side arms of a reclining chair, or similar article of furniture, each of such arms having the front and back feet 11 and 12 respectively.

The numeral 13 designates the back which is pivotally supported between the two side arms for turning or swinging on a transverse axis extending across the chair at the rear upper part of the arms whereby it may be made to assume a substantially upright position or a horizontal position, in which latter position it is shown in Figure 1. Such axis may be provided by a cross rod 14 connecting the side arms 10 together and passing through the seat back 13 as shown in Figures 1 and 4, or any other suitable means may be employed for rotatably supporting the back.

The numeral 15 designates a seat. This is piv-

2

otally supported at its sides, and near the front, on pivots 16, which are carried by suspension arms 17, which arms are set into suitable recesses 17a formed in the inner sides of the arms at the front of the latter, to be positioned between the ends of the seat and the adjacent chair side arms 10. These suspension arms are pivotally suspended as at 18 from the chair side arms adjacent to the tops of the latter.

While the seat suspension arms may be made to terminate near the pivots 16, they are here shown as extending below the latter, when the seat is in normal lowered position, and have secured between them the heel pane 19, which assumes the character of a front wall panel for the chair, between the side arms 10, when the seat is lowered, as stated.

The numeral 20 designates a foot rest joined to the two side wings 21 which are each pivoted, as at 22, to one side of the panel 19, whereby the rest may be swung to a position against the face of the panel 19, or to extend outwardly from the bottom thereof as desired. The back edge of the rest 20 has a stop plate 23 which limits the downward swing of the rest as is readily apparent.

The seat is coupled at each side, at the back edge, to the lower part of the back, by the two downwardly curved arms 24. Each arm is integral at one end with a plate 25 which is secured to the side of the seat and the other end of the arm is pivotally coupled to the side of the back as at 26. Thus when the back is in normal position, the back edge of the seat will be drawn in against the front of the chair back as shown in broken lines, but when the chair back is swung on its pivots 14 the seat will move up and forward until it and the back are in horizontal position and in a common plane.

The mechanism for securing the seat and back in different positions of adjustment comprises two units which are, the keeper bar 27 and the lock unit 28.

The keeper bar comprises a long, flat arcuate bar body 29 having a series of slots or notches 30 cut in the convex edge thereof. At its upper end the bar is widened to form a bill 31, at the end of the convex edge, one edge of this bill leading into the last slot 30, as shown.

The keeper bar unit 27 is fixed to the inner side of one side arm 10 by means of screws 32 passing therethrough, and through spacer washers 33, into the arm, as shown in Figure 3. The lower end of the bar is positioned to be at the bottom edge of the seat back when the latter is in normal upright position, and curves forwardly and upwardly so that its upper end will be near the top of the seat when the latter is in its lowermost position.

Fixed to the side of the seat, near the back edge thereof and adjacent to the keeper bar unit 27, is the lock unit 28 which is designed for selective coupling with the bar at the notches 30.

The seat carrying lock unit 28 comprises a plate 34 having a mounting flange 35 which is secured, as shown in Figure 3 to the seat bottom so that the plate 34 is in the plane of the adjacent side of the seat and is in spaced parallel relation with the bar 29.

In spaced relation to the plate 34 and between the latter and the bar 29 is a cover plate 36, held to the plate 34 by rivets 37 and spacers 38.

Mounted between plates 34—36 to swing on the pivot pin 39 is a bolt plate 40, which extends downwardly and rearwardly to provide the locking bolt 41, which terminates in the inwardly directed lip 42. This lip 42 projects across the plane of the keeper bar body 29 and is disposed so as to enter a slot 30 when the bolt is swung up toward the bar body.

Below and forwardly of the plate 40 a leaf spring 43 is secured upon a pin 44 and bears at one end against the under edge of the plate 40 to constantly urge the latter to swing upwardly for engagement of the bolt lip 42 with the bar body.

The top edge of the plate 40, near to the pivot 39, is cut to provide a semi-elliptical recess or socket 45, between two horns 46 and 47, the purpose of which will hereinafter be pointed out.

Below the lower horn 47 and rearwardly therefrom is fixed, between the plates 34—36, a stop pin 48 which limits the upward swing of the bolt 41. The down swing of the bolt is limited by a similar stop pin 49, located above and forwardly of the pivot 39, and contacted by the terminal ear 50 forming an extension of the bolt plate 40.

Mounted on the pivot pin 51, which is positioned between the plates 34—36 rearwardly of the pivot 39 and in line with the socket 45, is the bolt operating lever 52. The pivot pin 51 passes through the lower end of this lever and the lever extends upwardly across the adjacent side of the seat and carries upon its upper end, above the level of the seat top, the knob 53.

The lower end of the lever 52 carries the forwardly directed short arm 54 which terminates in the forwardly directed, semi-circular head 55, and the upper and lower, forwardly facing stop shoulders 56 and 57 respectively which coact respectively with the flat ends of the adjacent horns 46 and 47.

The socket or recess 45 is, as stated, approximately semi-elliptical and has its long axis substantially vertical, while the lever arm head, is substantially semi-circular and of a size to position entirely within the recess 45, together with one shoulder.

At the outer end of each shoulder, is an outwardly bulging cam 58, which alternately engage, or work, in the socket in the action of disengaging the bolt from the keeper bar and releasing it for reengagement therewith.

Figure 1 shows the seat fully elevated, in which position the bolt lip is engaged in the top keeper bar slot 30, while Figure 2 shows the bolt lip engaged in a lower slot 30. As shown when the bolt lip is so engaged the lever arm head 55 is in the top end of the recess 45 and the shoulder 56 is opposed to and engaged by the horn 46. The bolt is thus locked against downward swinging as long as the lever is untouched.

If the lever is swung forward to the position shown in broken lines the cam 58 below the shoulder 57 presses into the lower part of the recess to force the bolt 41 down and release the lip 42 from its slot and when the arm has swung to the position shown in broken lines the shoulder 57 will engage the end of the lower horn 47 and

thus secure the bolt in open, or unlocked, position.

To return the bolt to locked engagement with the keeper bar a reverse pull on the lever 52 will force the upper cam 58 against the upper part of the recess to reverse the operation.

From the foregoing it will be seen that there is provided in the present invention a relatively simple, easily operated locking mechanism, which can be made strong and durable and will be positive and reliable in operation.

I claim:

1. In a reclining chair, including spaced side arms, a back pivotally supported between the arms, a seat, a pivotal coupling between the bottom of the back and the back portion of the seat, swinging suspension means for the seat between the front portion of the seat and the arms, by which the seat is movable upwardly and forwardly by and upon the swinging of the back from an upright to a horizontal position, an arcuate keeper bar secured to one arm between the same and the adjacent side of the seat, a lock carried by the said side of the seat and comprising a pivoted bolt positioned to follow the curve of the bar upon up and down movement of the seat, means for coupling the bolt to the bar at selected positions along the latter, a lever pivoted to the seat, and means coupling the lever to the bolt by which swinging of the lever effects movement of the bolt into and out of locking connection with the bar.

2. A locking mechanism for coaction with a relatively long keeper bar comprising a lock unit movable lengthwise of the bar, a bolt plate pivoted on the unit to swing on an axis disposed transversely of the bar, a bolt carried by said plate and having means thereon adapted for locking engagement with the bar at selected locking means positions therealong, means facilitating the said locking engagement of the bolt at selected positions therealong, a lever pivoted on the unit adjacent to the plate, a recess in the plate, a head carried by the lever and loosely engaging in said recess, the lever when swung on its pivot from either of two positions effecting swinging of the plate to shift the bolt relative to the bar, and coacting locking means between the lever and plate to secure the plate against shifting from its locked or from its unlocked position.

3. A locking mechanism as set forth in claim 2, wherein the said coacting locking means comprises a stop shoulder at each of two opposite sides of the head and an abutment surface at each end of the recess in the plate, one of said shoulders being in engagement with the adjacent abutment surface in the locked and unlocked positions of the bolt.
